(57) CLAIM

The ornamental design for an outsole, as shown and described.

DESCRIPTION

This application is related to co-pending U.S. Design patent application Ser. No. 29/867,653, filed on Nov. 2, 2022, entitled "Footwear," which is incorporated in its entirety by reference.

FIG. 1 is a front, bottom perspective view of an outsole, showing our new design;

FIG. 2 is a back, bottom perspective view thereof;

FIG. 3 is a bottom view thereof; and,

FIG. 4 is a front view thereof.

The dashed broken lines depict portions of the outsole that form no part of the claimed design. The dot-dashed broken lines represent boundaries of the claimed design and form no part of the claimed design.

The claimed design includes a second embodiment which is a mirror image of FIGS. 1-4.
